UNITED STATES PATENT OFFICE.

VINCENT F. SLEZAK, OF CHICAGO, ILLINOIS.

COIN-CONTROLLED WEIGHT-PRINTING MACHINE.

Application filed March 24, 1926. Serial No. 97,034.

The invention relates to new and useful improvements in coin controlled weight printing machines.

An object of the invention is to provide a machine of the above type wherein the tickets are supplied from a ticket strip, and wherein mechanism is provided for printing the ticket and subsequently severing the same from the strip while the ticket is in printing position, with a coin controlled mechanism for initiating first the printing mechanism and for subsequently initiating the severing mechanism after the ticket has been printed.

15 A further object of the invention is to provide a machine of the above type wherein the tickets to be printed are fed from an accordion folded strip and held suspended beneath the printing wheel solely by the attachment of the ticket to the strip, whereby when said ticket is severed from the strip it will fall by gravity and be delivered.

A further object of the invention is to provide a machine of the above type with a coin chute between the receiving slot and the trip lever for initiating the operation of the printing mechanism and the severing mechanism, which is so constructed as to lead a coin in a circuitous path whereby the type wheel has ample time to come to rest before the trip lever is actuated and the printing mechanism initiated.

25 A still further object of the invention is to provide a machine of the above type wherein the impression hammer for printing and the severing devices for severing the ticket from the strip are disposed beneath the printing wheel so that chips, dust and the like incident to printing and cutting 30 fall away from the printing wheel instead of on to the same.

A further object of the invention is to provide a mechanism of the above type which includes a weight actuated bar, which 35 weight actuated bar when released by the coin controlled trip mechanism after the printing of the ticket has been accomplished, operates to reset the impression hammer of the printing mechanism, actuates the severing devices, and resets the coin controlled trip mechanism and also operates to move the ribbon relative to the printing type.

40 A still further object of the invention is to provide a machine of the above type 45 wherein the weight actuated bar is raised to

a set position by the weight of the individual, and wherein said actuated bar, while being reset, operates to feed the ticket strip so as to suspend the ticket beneath the type ready for printing. 60

A still further object of the invention is to provide a coin controlled weight printing machine of the above type with a diverting chute for a coin, normally positioned so as to return the coin, but which is shifted by 65 the weight actuated bar when said weight actuated bar is raised to set position, so that the coin when dropped into the slot, will actuate the trip lever for controlling the printing and severing of the ticket. 70

A further object of the invention is to provide a coin controlled weight printing machine of the above type, wherein the printing roll is set by the downward movement of a rack bar moving in a vertical plane, 75 which downward movement of the rack bar is limited by a sealing segment connected to the platform of the weighing scales and controlled in its movement by a swinging link and a fixed fulcrum stud. 80

A further object of the invention is to provide a machine of the above type with a coin controlled device for indicating the height of the individual being weighed, which coin controlled device is reset for further actuation by the upward movement of the platform when the individual steps therefrom. 85

These and other objects will in part be obvious and will in part be hereinafter more 90 fully disclosed.

In the drawings which show by way of illustration one embodiment of the invention—

Figure 1 is a front view of a machine embodying the improvements; 95

Fig. 2 is a front view of the main supporting plate within the casing of the machine and the mechanism supported thereby;

Fig. 3 is a rear view of the supporting 100 plate and the mechanism supported thereby;

Fig. 4 is an enlarged detail view of the coin controlled initiating devices for the printing mechanism and the actuating bar;

Fig. 5 is an enlarged detail of the sealing segment for positioning the type wheel; 105

Fig. 6 is an enlarged view of the coin chute for conveying the coin from the slot to the coin chute leading a coin to the trip lever; 110

Fig. 7 is a detail in plan showing the actuating mechanism for positioning the scale which indicates the height of the individual;

Fig. 8 is a view partly in section and partly in side elevation of said mechanism for positioning the scale;

Fig. 9 is a bottom plan view of the platform of the weighing scales and the parts directly associated therewith;

10 Fig. 10 is a sectional view on the line 10, 10 of Fig. 9;

Fig. 11 is a perspective detached view of the actuating lever which lifts the actuating bar and the tripping devices which releases 15 the actuating lever.

The invention is directed broadly to a coin controlled weight printing machine, wherein the tickets on which the weight is printed, are delivered to the machine from 20 an accordion folded strip as distinguished from the hopper containing single tickets, or from a roll of tickets. The printing is accomplished by a printing wheel and a cooperating printing hammer. The hammer is located beneath the printing wheel, and the ticket is projected between the hammer and the printing wheel by a feeding forward of the ticket strip, and the ticket is held in position for printing solely by 25 its attachment to the strip. Associated with this printing mechanism are severing devices which are timed to sever the ticket from the ticket strip after it has been printed, and when the ticket is severed from 30 the strip, it will fall by gravity and be delivered from the machine.

The severing device and the hammer are all disposed beneath the printing wheel, so that any chippings or fragments of paper, 40 dust or the like, will fall away from the printing wheel rather than on to it. The printing wheel is set by a rack bar which moves in a vertical line, said wheel being at a zero point when the rack bar is at the 45 upper end of its movement, and is turned to printing position by the downward movement of the rack bar. The downward movement of this rack bar is determined by a sealing segment which is connected to the 50 platform of the weighing scales and which is supported by a link and a fixed pivot stud with which it has a sliding engagement. This sealing segment is moved to a predetermined position by the weight of the individual. The sealing segment has a relatively 55 long engagement with the pin on the lower end of the rack bar, which provides for a very ready shaping of the segment in the sealing of the machine. The printing hammer is spring actuated and is tripped at the proper time for printing by a coin controlled mechanism. The severing device is actuated by means of a weighted bar which is latched in raised position, and the latch 60 is released by the coin controlled mechanism.

This coin controlled mechanism is so designed as to first trip the printing hammer and subsequently trip the actuating bar for the severing device. This actuating bar as it descends to actuate the severing device, 70

resets the printing hammer and thus the printing hammer is moved out of the way before the ticket is severed, and therefore, it is free to drop. The downward movement 75 of this actuating bar not only actuates the severing device, but unlatches the severing device after it is actuated so that it may return to normal position. The downward movement of this actuating bar also resets the trip lever controlled by the coin and 80

the intermediate devices controlled thereby. These intermediate devices are for the purpose of first tripping the printing hammer and subsequently releasing the latch for the actuating bar. They are spring operated, 85 and they are also reset by this downward movement of the actuating bar. This actuating bar is moved downward by a weight and is lifted by a connection with the platform of the weighing scales. The platform 90 of the weighing scales is pivoted so as to have a movement independent of the movement of the frame which controls the printing wheel and thus determines the weight of the individual. This independent movement of the platform through suitable mechanism, raises the actuating bar and is then disconnected therefrom, all on the downward movement of the platform, when the person to be weighed steps thereon. While 100

this is being accomplished, the frame moves downward and the setting of the printing wheel occurs. The upward movement of the actuating bar not only lifts it to its position where it can be latched and held until released by the coin, but, on its upward movement, the printing strip is fed forward beneath the printing wheel and thus positioned for the printing of the ticket. Also on the upward movement of the actuating 110 bar, the ribbon is moved slightly to present a new surface to the type.

Associated with the coin chute is a diverting chute which is held by means of a latch so as to divert the coin, and prevent it from operating the trip lever. This latch is released, however, by the upward movement of the actuating bar when it reaches the extreme upper end of its movement and is in position to be latched. When the diverting 115 chute is released, it is swung by a weighted arm so as to direct the coin into the chute for operating the trip lever. Above this diverting chute is a receiving chute for the coin which is shaped so as to delay the delivery of the coin to the trip lever, and the purpose of this delayed delivery of the coin is to enable the printing wheel to come to a fixed or standing position. The portion of the 120 coin chute adjacent the receiving slot of the 125

machine is V-shaped so as to prevent the clogging of the coin. The diverting chute and the portion of the coin chute beneath are of such size as to permit the coin to drop 5 sidewise as well as edgewise. In other words, there is no possible chance of the coin clogging after it is once inserted in the machine, until it comes in contact with and operates the trip lever. The means for indicating the 10 height of the individuals standing on the weighing platform is, in the present embodiment of the invention, controlled by an independent coin. This height indicating device consists of a mirror on the front face 15 of the machine in which there is a clear strip of glass hereinafter referred to as a slot. Behind this clear strip of glass is a movable member on which the measuring scale is placed. This movable member is normally 20 positioned so as not to be viewed through the slot. There is a segment lever for rotating or positioning this member carrying the scale. This segment lever is turned by means of a spring in one direction, and 25 is held by means of a latch from turning. A coin controlled trip lever holds the latch from operating said segment. The person standing on the platform desiring to know his height, drops a coin through the 30 slot, and the coin engaging the trip lever will release the segment so that the movable scale will appear to view in the slot in the mirror face of the machine. The image of the person standing on the platform appears on 35 the mirror, and thus it is that the height of the individual can be determined. The resetting, or the moving of the scale to its normal position where it is hidden from view, is brought about by the upward movement 40 of the rack controlling the printing wheel, and this upward movement of the rack occurs when the individual being weighed steps from the platform and the 45 platform is returned to normal position.

Referring more in detail to the drawings, 50 my improved coin controlled weight printing machine includes a main casing 1, at the base of which is located the portion of the weighing scales 2, which includes a platform 3 on which the individual stands for weighing. At the sides of the casing are the usual hand rails 4. The front of the casing is provided with a mirror 5 on which various indications can be made. This mirror is provided 55 with a slot 6. Associated with this mirror and slot is a scale which is normally concealed from view, but which, upon the dropping of a coin in the slot 7, is operated so that the height of the individual standing 60 on the platform can be determined. The scale is so constructed that the height of the individual is determined by the height of the eyes reflected in the mirror, and indications to this effect are printed on the front 65 face of the machine. Other suitable infor-

mation may be printed on the face of the casing having relation to the height and weight of the individual.

The weight of the individual is obtained by printing the same on a ticket through the aid of coin controlled mechanism. The coin is dropped in the slot 8 in the front of the casing and passes down through a series of coin chutes 9, 9 arranged at an angle to each other, so that the coin drops from one chute 75 to another and runs along the same on edge. These chutes are each V-shaped in cross section as clearly shown at 10 in Fig. 3 of the drawings. The purpose of this V-shaped chute is to prevent the coin from being 80 clogged through the wrapping of the coin in paper when it is forced through the coin slot 8 by an individual who desires to tamper with the machine. The coin after it leaves the last chute 9 will fall into the diverting 85 coin chute 11, which either directs the coin into the main chute 12 or the auxiliary chute 13 associated therewith. When the parts are positioned as shown in dotted lines in Fig. 3, the coin will pass into the auxiliary chute 13 90 which will direct the coin out through the opening 14 in the main supporting plate 15, and this will lead the coin to the receptacle 16 at the front of the casing. The purpose of this diverting chute is to return the coin, 95 provided the parts are not properly set for printing the ticket and severing the same from the ticket strip. When, however, the parts are properly positioned for actuation, then the diverting chute is in the position 100 shown in full lines in Fig. 3, and the coin will pass down through the main chute 12 and engage the trip lever 17. The diverting chute as well as the main coin chutes are each square in cross section so that the coin 105 can pass therethrough either edgewise or flatwise.

At the front side of the main supporting plate 15 is a type wheel 18 provided with a series of printing type. This type wheel is 110 mounted in suitable ball bearings 19 and 20. The ball bearing 20 is carried in a bracket frame 21 bolted to the main supporting plate 15. The type wheel rotates very freely on its ball bearing support and carries a pinion 115 22 which meshes with a rack bar 23. The rack bar is free to move vertically and is held in proper cooperative relation to the pinion by a guide roller 24. At the lower end of the rack bar 23 is a pin 25 which is 120 rigidly attached thereto. Said pin is adapted to engage a sealing segment 26. This sealing segment 26 is pivoted at 27 to the outer end of a swinging link 28 which in turn is pivoted at 29. The sealing segment 125 26 has a slotted arm 30 which engages a fixed fulcrum pin 31. Also pivotally joined to the sealing segment 26 is a link or bar 32. The lower end of this bar 32 is connected to an adjusting screw 33 which extends 130

through a cross-head 34, and is held in adjusted position on the crosshead by means of nuts 35, 35. The crosshead 34 is suspended by springs 36, and this crosshead is connected by means of a rod 37 to the usual devices which are moved by the platform 3 of the weighing scales. When the individual to be weighed steps on the platform, the rod 37 will be pulled down, stretching the 10 springs 36 to a predetermined extent, depending upon the weight of the individual. When the individual steps off from the weighing platform, then the springs will return the platform to its raised position. 15 When in this raised position, the sealing segment is raised to its highest position as indicated in Fig. 5, and this lifts the rack bar 23 and brings the type wheel back to normal zero position. This is determined by 20 the line 38 in conjunction with the supporting bracket (see Fig. 2). If the type wheel is not on its zero mark at this time, then the adjusting screw is manipulated to bring it to its proper zero indication. This type 25 wheel is not for the purpose of indicating the weight, but for printing the weight on the ticket. Nevertheless, the type wheel must start at the proper zero mark in order to print the proper weight of the individual. 30 When the individual steps on the platform, the crosshead 34 is moved downwardly as noted above, and this lowers the sealing segment 26 and permits the rack bar 23 to move downward through its weight, and this turns 35 the printing wheel. The extent to which the printing wheel is turned depends upon the downward movement of the rack bar, and the extent of downward movement of the rack bar is determined by the sealing segment. 40 The type wheel is mounted in ball bearings as indicated above, and as a result, the rack bar will often move up and down for a very brief interval until it comes to rest. The printing of the ticket, of course, 45 cannot be accomplished until the type wheel is at rest. The purpose of this zigzag arrangement of coin chute is to lead the coin in a circuitous path after it has been dropped in the slot at the left of the casing, so as 50 to give the type wheel ample time to come to a fixed or stationary position before the printing is effected, through the releasing of the trip lever by the coin. This segment 26 has been referred to as a sealing segment 55 for the reason that it is used as a means for sealing the weighing mechanism. If it is found that the printing wheel is not properly positioned for a weight, say, for example, of sixty pounds, then the surface of the 60 sealing segment may be scraped or filed in order to bring about a correct positioning of the type wheel. Said segment may be raised or lowered bodily by adjusting the screw 33, if the type wheel indicates overweight. 65 It is noted that this sealing segment is very accessible so that it may be readily scraped or filed without being removed from the machine. Not only is it accessible, but the surface which is to be scraped or filed is on the upper side of the sealing segment, so that the sealer can readily see the effect of the scraping or filing as it proceeds. It will be noted, too, that this sealing segment 26 has a very long surface with which the pin 25 makes contact. This is accomplished 70 through the aid of the link 28 and the fixed fulcrum stud 31. Through the aid of this long surface contact, the sealing of the weighing mechanism can be very much more efficiently and accurately accomplished, as 75 the difference between points of engagement between the pin and the sealing segment for different increments of weight to be indicated, is sufficient to allow for the scraping or filing of the same during sealing without interfering with the portions of the segment which determine increments of weight close by. 80 The weight of the individual is printed on a ticket and the ticket is supplied from a ticket strip 39. This ticket strip is stored in a receptacle 40 secured to the lower portion of the supporting plate 15, and this receptacle may extend well down toward the base of the casing. The strip is placed in the receptacle by the folding of the same accordion fashion, that is, it is folded back and forth. Each fold in the strip contains a number of tickets to be printed. This strip has several advantages. In the first place, 85 the ticket to be printed is supported solely by its attachment to the ticket strip. Where the ticket strip is maintained in its source of storage in a straight condition, it will aid greatly in the positioning of the ticket 90 properly relative to the type wheel. In other words, that portion of the ticket which is to be printed will be held in a horizontal position and will be fed forward in a horizontal position, without curving downwardly as is often the case where the ticket strip is in roll form. Furthermore, in a ticket strip which is folded as stated above, the supply may be added to at any time merely 95 by lifting the folded tickets in the machine 100 and placing beneath the same a new supply of folded tickets, and attaching the end of the last ticket in the supply which was in the machine to the first ticket at the end of the new supply, and thus it is that the outgoing strip will carry the new supply into the machine. This ticket strip passes around a feed roller 41 which is of the usual construction, and is fed through suitable guides 105 between severing devices. One of these severing devices is a stationary ledger blade 42, while the other is a movable shearing blade 43. This movable shearing blade is pivotally mounted on a pivot bolt 44 which in 110 turn is mounted in a lug 45 formed as a 115 120 125 130

part of the casing which contains the feed roll for the ticket strip. A spring 46 normally presses the pivoted end of the movable blade toward the ledger blade. This movable blade extends through the supporting plate 15 as shown in Fig. 3. The movable blade is normally pulled downwardly by a spring 47 and is raised for cutting the ticket by means of a lever 48 which is pivoted at 49 to the rear face of the supporting plate 15. The blade is held at its free end in contact with a guide plate 50 by means of a swinging arm 51 which is pivoted at its lower end and pulled against the blade by the spring 52. This movable blade is held yieldingly pressed in proper position for making a sheer cut with the ledger blade and insures that a ticket will be severed from the strip when the movable blade is operated.

Returning again to the front face of the supporting plate 15, the ticket strip after passing between the severing devices, is led between suitable side guides 53. These side guides merely position the ticket relative to the printing devices. In addition to the type wheel which will print the weight of the individual, there are also type wheels 54 adapted to be set by means of a hand member 55 for the printing of the proper date. This mechanism has not been shown in detail, as it is of the usual construction. It will be noted that the ticket projects beyond the severing mechanism, and lies between the guides 53 directly beneath the type wheels, and is held suspended solely by its attachment to the ticket strip of which it is a part.

The printing of the ticket is effected by means of an impression lever or hammer 56 which is fixed to a shaft 57. Said impression lever has a rearwardly projecting portion 58 which is connected to a spring 59. This spring 59 normally turns the lever 56 in a counter clockwise direction as viewed in Fig. 2, and brings the hammer portion 60 thereof up against the ticket and the ticket against the type so that the date is printed thereon.

An inked ribbon 61 passes over suitable rollers, one of which is indicated at 62 and over a feed roller 63. This ribbon passes between the type and the ticket to be printed, so that the ribbon will lay close to the upper face of the ticket, and when the impression hammer is actuated by the spring 59, it will strike the under face of the ticket and force the upper face of the ticket together with the inked ribbon, against the type. The inked ribbon is fed by means of a ratchet wheel 64 which is operated by means of a pawl 65 as will be hereinafter more fully described. The ticket strip feed roll 41 is actuated by means of a ratchet wheel 66. This ratchet wheel 66 is turned by the pawl 67 carried by a swinging arm 68

which is oscillated by a link 69 connected to a lever 70. The lever 70 is provided with an arm 71 moved by a spring 72 in a downward direction. Said arm is raised by a pin 73 as will be hereinafter described. Whenever this pin is raised, it will swing the lever 70 so as to turn the feed wheel 41 and project the ticket across the face of the type wheel for printing.

On the rear end of the shaft 57 carrying the hammer or impression lever for printing, is an elbow lever 74 (see Fig. 3). The arm 75 of this elbow lever is notched at 76 (see Figures 3 and 4). A trip lever 77 carries a pin 78 which drops into the notch 76 when the shaft 57 is turned in a clockwise direction as viewed in Fig. 4. This turning of the shaft 57 is accomplished by means of an actuating bar 79 which is mounted to slide vertically in suitable keepers on the rear side of the main supporting plate 15. This actuating bar is moved downwardly by a weight 80. The downward movement of the bar causes the roller 81 carried thereby to engage the cam face 82 of the upwardly projecting portion of the elbow lever 74. This roller when it engages the elbow lever will turn the shaft in a counter clockwise direction as viewed in Fig. 4, and the turning of this shaft in a counter clockwise direction will store power in the spring 59 on the front face of the supporting plate. This impression lever or hammer is therefore held from movement by the latch lever 77, and when said latch lever is swung so as to release the elbow lever 74, then the stored power in the spring 59 will at once actuate said hammer or impression lever so as to print the ticket.

The coin controlled lever 17 is pivoted at 83 to the main supporting plate 15. Said lever is provided with a weighted end 84, and with a rigid latch 85. A lever 86 is pivoted at 87 and is normally raised by means of a spring 88. Said lever is held in its lowered position against the tension of the spring 88 by means of a pin 89 which is held down by the latch 85 of the coin controlled lever 17. At the outer end of this lever 86 there is a pin 90. Pivoted to the latch lever 77 is a bar 91. This bar 91 is provided with a notched shoulder 92. The bar passes through a keeper 93. Said bar is provided with a recessed portion 94. When the latch lever 77 is in position for holding the printing hammer from movement, then the bar 91 is in its lowest position, and the shoulder 92 is in the path of movement of the pin 90 on the swinging lever 86. When the coin controlled lever 17 is tripped, this lever 86 is moved upwardly by the spring 88 and the pin 90 will engage the shoulder 92 and raise the bar 91. This will swing the latch lever 77 and release the printing hammer. Thus it is that

the coin upon operating the lever 17 releases the spring actuated lever which first operates to release the latch lever which holds the printing hammer from movement 5 through the actuation of the power stored in the spring 59. As the bar 91 moves upwardly, the lower edge of the recess 94 which is inclined, will engage the side wall of the slot with the keeper 93 through which this 10 bar passes. This will force the bar laterally at its lower end, and thus withdraw the shoulder 92 from the path of movement of the pin 90, and allow the lever 86 to continue its upward movement. As noted 15 above, the actuating bar 79 carries a weight 80 which normally pulls down on this actuating bar. The actuating bar is provided with a shoulder 95. A locking dog 96 pivoted at 97 is provided with a lug 98 which is 20 adapted to engage underneath the shoulder 95 and hold the actuating bar in raised position. This dog 96 rests on a pin 99. The dog 96 at its outer end lies in the path of movement of the outer end of the swinging 25 lever 86. As soon as the swinging lever 86 is released from the bar 91, it will continue its upward movement and strike the locking dog 96 and lift the same so as to release the actuating bar. It is noted that this lever 30 86 cannot continue its upward movement to release the actuating bar until the latch for the printing hammer has been released, for the reason that it is the upward movement of the bar 91 which turns the latch lever 77, 35 and this bar 91 will prevent the upward movement of the lever 86 until the bar has reached the upper end of its movement and swung laterally so as to release the pin 90. This insures that the printing lever shall 40 be released and the printing effected at a considerable interval before the actuating bar is released.

Mounted on the actuating bar is an actuating dog 100. This actuating dog 100 moves 45 up and down with the actuating bar. At the lower end of the depending arm of the actuating dog 100 is a lug 101 which is adapted to engage the outer end of the lever 48 which actuates the movable severing member. When this actuating member 79 moves 50 downward through the weight 80 carried thereby, and after the locking dog 96 has been released, this actuating dog 100 will move the lever 48 so as to raise the movable blade and sever the ticket from the ticket strip. It will be noted that the ticket is 55 printed before the actuating bar is released, and the actuating bar in its downward movements operates the severing device, and 60 therefore, while the actuating mechanism is all controlled by a coin, it is so constructed that when the coin releases the actuating mechanism, the ticket is first printed and 65 is then subsequently severed, so that it may drop by gravity and be delivered through

the opening 16 to the front of the casing. There is a suitable receptacle or chute 102 directly beneath the printing position of the ticket into which the ticket drops and it is led from the chute out through the opening 16. 70

It will be noted from the above that the ticket is moved by the feed wheel to a position to be printed, and remains in this position until it is printed, and after it is printed, then it is severed. In other words, there is only one feed stroke for each weight printing and severing operation. The dog 100 which operates the severing device, is pressed by means of a spring 103 against the pin 104 80 mounted on the actuating bar. As this dog moves downward with the actuating bar, it strikes a pin 105 on the main supporting plate 15 which moves the dog outward at its lower end, thus releasing the lever 48, and when the lever 48 is released, the spring will at once turn the same so as to lower the movable severing member, and thus it is that the severing mechanism is left with the movable blade lowered so that the next ticket to be 85 printed may be projected through between the blades to printing position beneath the type wheels. 90

The pin 73 referred to above for actuating the ticket strip feed is mounted on this actuating bar 79, and the upward movement of the actuating bar feeds the ticket. The downward movement of this pin engages the lever 86 and lowers the lever to a position where it will be locked down by the latch 100 95 105. Thus it is that the downward movement of the actuating bar resets the devices controlled by the coin, which first releases the printing mechanism and then the severing mechanism. The dog 65 which actuates the ribbon feed is also mounted on this actuating bar 79, and it is the upward movement of the bar which feeds the ribbon. This actuating bar is lifted by means of a rod 106. This rod 106 is raised by the weight of the individual on the platform of the weighing scales as will be soon described. The weight of the individual lifts this actuating bar and as soon as the actuating bar is in its extreme 110 uppermost position, the dog 96 will hold the actuating bar until it is released by the coin. 115

The coin diverting chute 11 is pivoted at 107 to the supporting plate 15. A weighted arm 108 normally swings said chute to the full line position shown in Fig. 3. The chute is connected by means of a link 109 to a swinging arm 110. This arm 110 is pivoted at 111 to the supporting plate 15. A spring 112 normally presses the swinging arm 110 to the left as viewed in Fig. 3, and further aids in maintaining the diverting chute in the position shown in full lines. This spring 123 may be omitted when the weighted arm 108 is used. Projecting laterally from the 130

weighted bar 79 is a lug 113 which carries a pin 114. The arm 110 carries a pin 115 on which a latch 116 normally rests. This latch is provided with a shoulder 117. When the 5 weighted bar 79 is released and drops, the pin 114 will engage the inclined portion of the arm 110, and this will force the arm to the left to the dotted line position shown in Fig. 3. This movement of the arm 110 to 10 the left swings the diverting chute to the dotted line position shown in this Figure, and thus the chute is positioned so that the coins will pass through the auxiliary chute 13 and be returned to the operator. When 15 this arm 110 is moved to the dotted line position, the latch lever 116 will drop so that the pin 115 will be locked against the shoulder 117 of the latch 116. When the weighted bar is raised to latching position, so that it 20 will be held raised until the coin releases the same, the latch 116 is engaged by the pin 113 and raised so as to release the arm 110, but this releasing of the latch 116 is not accomplished until the weighted bar is raised 25 to a position where it can be latched. In other words, the coin diverting chute remains set in the dotted line position until all of the parts which are actuated during the raising of the bar 79 are in proper position for actuation 30 when a coin is dropped into the slot.

The platform 3 of the scales is pivoted at 118 to the weighing frame 119, which is of the usual construction, so far as the manner of supporting the same, and the operating 35 of the rod 37 is concerned. That is to say, this weighing frame is moved downwardly through the weight of the individual on the platform of the scales, and as this frame goes downward, the rod 37 is also moved 40 downward, stretching the springs 36, and the extent of downward movement of the weighing frame is determined by the weight of the individual. The weighing frame, is, of course, raised when the individual steps 45 off the platform by the springs 36. As above noted, the platform 3 is pivotally connected to the weighing frame 119. The right-hand or rear end of the platform 3 is raised by means of the arms 120 which carry a weight 50 121. The upward movement of the rear end of the platform is limited by the stop screws 122 which passes through perforated lugs 123 mounted on the weighing frame. It will be understood, of course, that these weighted 55 arms move up and down with the weighing frame. Also pivotally mounted on the weighing frame is an operating lever arm 124. Said lever arm 124 is pivoted at 125 to the weighing frame and projects forward- 60 ly beyond the front end of the platform to a point underneath the rod 106. Mounted adjacent the rear edge of the platform 3 is an arm 126 provided with a lug 127. Said arm 126 is moved about its pivot point by 65 means of a weighted arm 128 which is rigid therewith. This moves the arm 126 so as to position the lug 127 over a projecting pin 129 on the actuating lever arm 124.

When the individual to be weighed steps on the platform 3, it will depress the weighing frame and will also depress the rear edge of the platform, turning the same about its pivotal support 118. As the rear edge of this platform moves downward, the arm 126 will force the right-hand end of the operating lever 124 downward, and the inner end of this operating lever arm will be raised until it engages the rod 106. The swinging of the platform 3 on its pivot will therefore, raise the rod 106. When the platform is 70 moved downwardly relative to the weighing frame a sufficient distance, the weighted arm 128 will strike the lug 123 and release the arm 126 from the pin 129. Thus it is that 75 on the downward movement of the rear edge 80 of the platform, the lever 124 first operates to raise the rod 106, and then the lever is released, so that the left-hand end thereof drops away from the rod 106. The weighing frame and the platform will, however, 85 remain down as long as the individual stands thereon. The purpose of releasing this operating lever is to get it out of the way of the rod 106, so that the rod 106 may be moved downward while the individual still 90 stands on the platform 3. The upward movement of the rod 106 raises the weighted bar 79, and the raising of the weighted bar 79 stores power which is held by the latching 95 of the weighted bar until the coin releases the weighted bar so that it can drop. This platform 3 is well above the base of the machine and above the floor, so that its downward movement relative to the base, both 100 due to the swinging of the platform on the weighing frame and the downward movement of the weighing frame, cannot by any possibility pinch the foot of an individual standing close to the base. It will be apparent, therefore, that I have provided a 105 coin controlled machine for printing the weight of an individual wherein the weighing of the individual is accomplished by the movement of the platform on which the individual stands, and wherein the storing of 110 power for operating the parts is also accomplished by a movement of the platform on which the individual stands relative to the base of the machine. The weight of the individual not only stores power in the 115 weighted bar which is raised and latched in raised position, but the upward movement of this weighted bar to a position where it can be latched, also operates 120 to feed the ticket strip so as to place a ticket in position to be printed. When the individual steps on to the platform, the type wheel turns to a position so as to print the weight of the individual on the platform, and the feed for the ticket strip pro- 125 130

jects the end of the ticket strip to a position relative to the type wheel so that the weight can be printed thereon. The weight of the individual through the raising of this 5 weighted bar to latched position where sufficient power is stored for operating the parts, also releases the diverting coin chute so that when a coin is dropped it will become effective to trip the actuating latch 10 which sets into motion the mechanism for printing the ticket and subsequently severing the same from the ticket strip. When the coin actuates the trip lever it first causes the operation of the printing hammer, and 15 this is brought about by power stored in the spring which is put there by the downward movement of the weighted bar so that the stored power from the weight of the individual which actuates the weighted bar, 20 also stores power when it is actuated, which power is utilized for the operating of the printing hammer. There are comparatively few parts in my machine which have to be actuated, and therefore, the weight 80 can 25 be comparatively light. This insures that an individual weighing not to exceed twenty pounds can depress the weighing platform sufficiently to raise the weighted bar until it is latched in raised position. My improved 30 coin controlled weight printing machine can therefore be used for weighing individuals from as low as twenty pounds up to the ordinary maximum. The operating lever 124 is so pivoted intermediate its ends, that 35 the left-hand end thereof will drop when the arm 126 releases the right-hand end of the lever, and the lever will move upward until the right-hand end thereof engages the lug 130. When the platform returns to its 40 normal position, it will, of course, raise the sealing segment and this will turn the printing wheel to zero position.

In rear of the slot 6 is a member 131 which is provided with a scale indicating the 45 height of the individual standing on the platform of the weighing scales. This scale is so placed on this member 131 that when it is rotated about a vertical axis to a certain extent, it will be concealed from view. At 50 the lower end of the rotatable member 131 is a pinion 132. Said pinion meshes with a segment lever 133 pivoted at 134. Upon the oscillation of this lever 133, the member 131 is turned so as to position the scale in front 55 of the slot, or to conceal the scale from view. The member may be provided with a suitable advertisement on the face which is exposed to view when the scale is concealed. A spring 135 engages a pin 136 on the frame 60 at one end thereof, and engages a pin 137 on the segment lever. This spring normally turns the segment lever so as to rotate the member 131 so as to conceal the scale. The segment lever is moved so as to position the 65 scale so that it can be viewed through the slot

by means of a bell crank lever 138. This bell crank lever is pivoted at 139 and is moved by means of a spring 140 so as to engage an arm 141 of the segment lever and move said arm against the tension of the 70 spring 135 to bring the scale into view. The lever 138 has an arm 142 which lies in the path of movement of the upper end of the rack bar 23. The rack bar is raised when the individual gets off the platform through the action of the spring 36. The upward movement of the rack bar swings the bell crank lever 138 so that the upper end thereof is moved to a point where the latch 143 having a lug 144 thereon drops behind a projection 145 on the bell crank lever and holds the bell crank lever from movement under influence of the spring 140. When this bell crank lever is moved away from the arm 141, the spring 135 will turn the segment lever 80 85 133 so as to move the member 131, whereby the scale is concealed from view through the slot. Thus it will be seen that when an individual who is being weighed steps off from the platform, the upward movement of the platform operates to turn the scale to a position where it is concealed and the latch lever 143 will hold the scale in this position. When a coin is dropped through the slot 7 at the right of the machine, it will strike the 90 end 146 of the latch 143 and will release the latch so that the individual standing on the platform of the scales can view through the slot 6, the scale which has been released and turned so as to be viewed through said slot. 95 The scale is so positioned on this member 131 that the height of the individual is measured by a line through the eyes. The face of the machine is the mirror, and as one stands on the platform, their image is reflected in the mirror, and a line through the eyes determines the height of the individual. The individual, however, cannot determine his height without dropping a coin in the slot at the right of the machine so as to release the scale and bring it into view. 100 105 110 It is not thought necessary to describe any further in detail the operation of the machine. Attention, however, is directed to the fact that when the operator steps upon the platform to be weighed, he can at once drop his coin in the slot, and the path which the coin must pass through before it trips the coin controlled lever is of sufficient extent 115 so that the type wheel comes to a standing 120 position. The downward movement of the platform as above noted, also causes the ticket to be printed to be projected between the severing devices to printing position beneath the type wheel. The type wheel is now positioned for printing and the ticket is in place to be printed. Power is also stored for operating the printing hammer, and is also stored for operating the severing devices. When a coin is dropped into the 125 130

control slot, it releases a train of devices which are so timed and actuated that the printing of the ticket is first effected, and after the ticket has been printed and the 5 impression hammer moved away from printing position, then the ticket is severed, and the severing of the ticket allows it to drop by gravity and be delivered by the machine. Just as soon as the ticket has been severed, 10 the severing devices are separated so that the next ticket can be projected between the severing devices into place for printing before the next severing operation is effected.

The machine consists of few parts, so that 15 there is no liability of its getting out of order. It is so constructed that the coin slot and the chute leading therefrom cannot become clogged, and therefore, the machine is very durable and serviceable. It can be 20 readily re-charged with a ticket strip, no matter what the condition of the ticket strip in the machine is at the time of re-charging with the new strip, as an accordion-folded strip permits of the new strip to be hitched 25 on to the end thereof so that it can be taken up and carried into the machine when the supply that is in the machine is exhausted. The construction and arrangement of the 30 coin chute set forth above forms the subject-matter of my divisional application Serial No. 144,045, filed October 25, 1926. The sealing device which permits of the calibrating of the machine to bring about the printing of the accurate weight of individuals, 35 forms no part of the present invention, but is shown and claimed in my co-pending application Serial No. 126,671, filed August 2, 1926.

It is obvious that minor changes in the 40 details of construction and the arrangement of the parts may be made without departing from the spirit of the invention as set forth in the appended claims.

Having thus described the invention, 45 what I claim as new and desire to secure by Letters Patent, is—

1. A coin controlled weight printing machine comprising a printing wheel, a weighing platform, means operated thereby for 50 positioning the printing wheel, a printing hammer located beneath said printing wheel, means for presenting a ticket to be printed between said wheel and said hammer, means for releasing the printed ticket whereby the 55 same drops by gravity, and coin-controlled devices for actuating the printing hammer and subsequently actuating the ticket releasing means.

2. A coin controlled weight printing machine comprising a printing wheel, a weighing platform, means operated thereby for 60 positioning the printing wheel, means for projecting a strip ticket into printing position relative to said wheel, an impression hammer, a spring for operating said ham- 65

mer, a latch for holding said hammer from movement by said spring, means for severing a printed ticket from the strip while said ticket is in printed position, and coin controlled devices for releasing the printing 70 hammer and subsequently actuating the ticket severing means.

3. A coin controlled weight printing machine comprising a printing wheel, a weighing platform, means operated thereby for 75 positioning the printing wheel, means for projecting a strip ticket into printing position relative to said wheel, an impression hammer, a spring for actuating the hammer, a latch for holding said hammer from movement by said spring, means for severing a printed ticket from the strip while said ticket is in printed position, and coin controlled devices for releasing the printing 80 hammer and subsequently actuating the ticket severing means, said impression hammer and said severing means being disposed beneath the printing wheel so that dust and chips released by the action of the impression hammer or the severing means, fall 85 away from said printing wheel.

4. A coin controlled weight printing machine comprising a printing wheel, a weighing platform, means operated thereby for 90 positioning the printing wheel, means for projecting a strip ticket into printing position relative to said wheel, said ticket being supported solely by the ticket strip of which it is a part, an impression hammer, a spring for actuating the hammer, a latch for holding 95 said hammer from movement by said spring, severing means for severing a ticket from the strip, and coin controlled means for releasing the impression hammer and subsequently actuating the severing means. 100

5. A coin controlled weight printing machine comprising a printing wheel, a weighing platform, means operated thereby for 105 positioning the printing wheel, means for feeding an accordion folded ticket strip and projecting the ticket at the end of the strip into printing position, and coin controlled actuating means for pressing the ticket against the printing wheel and for severing said ticket from the strip after it is printed. 110

6. A coin controlled weight printing machine comprising a printing wheel, a weighing platform, means operated thereby for 115 positioning the printing wheel, means for feeding an accordion folded ticket strip and projecting the ticket at the end of the strip into printing position, an impression hammer, severing means for severing the ticket from the strip, and coin controlled means for actuating the impression hammer and subsequently actuating the severing means. 120

7. A coin controlled weight printing machine comprising a printing wheel, a weighing platform, means operated thereby for 125 positioning the printing wheel, means for

feeding an accordion folded ticket strip and projecting the ticket at the end of the strip into printing position, an impression hammer, severing means for severing the ticket 5 from the strip, and coin controlled means for actuating the impression hammer and subsequently actuating the severing means, said impression hammer and severing means being located beneath the printing wheel so 10 that dust and chips released by the impression hammer and the severing means will fall away from said printing wheel.

8. A coin controlled weight printing machine comprising a printing wheel, a weighing platform, means operated thereby for 15 positioning the printing wheel, means for feeding an accordion folded ticket strip and projecting the ticket at the end of the strip into printing position, devices actuated from 20 the platform of the weighing machine when the individual steps thereon for actuating said feeding means, severing devices for severing a ticket from the strip, an impression hammer, and coin controlled means for actuating the impression hammer for printing 25 the ticket and subsequently actuating said severing devices.

9. A coin controlled weight printing machine comprising a printing wheel, a weighing platform, means operated thereby for 30 positioning the printing wheel, means for feeding an accordion folded ticket strip and projecting the ticket at the end of the strip into printing position, devices actuated from 35 the platform of the weighing machine when the individual steps thereon for actuating said feeding means, severing devices for severing a ticket from the strip, an impression hammer, coin controlled means for actuating 40 the impression hammer for printing the ticket and subsequently actuating said severing devices, a ribbon located between the ticket to be printed and the printing wheel, and means whereby said actuating means for 45 the severing devices moves said ribbon between printing operations.

10. A coin controlled weight printing machine comprising a printing wheel, a weighing platform, means operated thereby 50 for positioning the printing wheel, a spring actuated impression hammer, a latch for holding said impression hammer from movement under the action of said spring, a coin controlled trip lever and devices operated thereby for releasing said latch, means actuated by the weight of the individual on the platform of the weighing machine for re-setting said impression hammer, severing devices for severing a printed ticket from 55 the strip, and means whereby said severing devices are actuated at the time of the re-setting of the impression hammer.

11. A coin controlled weight printing machine comprising a printing wheel, a weighing platform, means operated thereby for 60

positioning the printing wheel, an impression hammer, a spring for actuating said impression hammer, a latch for holding said impression hammer from movement under the action of said spring, severing devices, a weight actuated bar for operating said severing devices, a latch for holding said bar in raised position, a coin controlled trip lever, and devices controlled thereby for first operating the latch to release the impression hammer and subsequently operating the latch for releasing the weighted bar. 70

12. A coin controlled weight printing machine comprising a printing wheel, a weighing platform, means operated thereby for 80 positioning the printing wheel, an impression hammer, a spring for actuating said impression hammer, a latch for holding said impression hammer from movement under the action of said spring, severing devices, a weight actuated bar for operating said severing devices, a latch for holding said bar in raised position, a coin controlled trip lever, devices controlled thereby for first operating the latch to release the impression hammer and subsequently operating the latch for 85 releasing the weighted bar, and means whereby the weight of the individual on the platform of the weighing scales raises said actuated bar to latched position. 90

13. A coin controlled weight printing machine comprising a printing wheel, a weighing platform, means operated thereby for 100 positioning the printing wheel, an impression hammer, a spring for actuating said impression hammer, a latch for holding said impression hammer from movement under the action of said spring, severing devices, a weight actuated bar for operating said severing devices, a latch for holding said bar in raised position, a coin controlled trip lever, devices controlled thereby for first operating the latch to release the impression hammer and subsequently operating the latch for releasing the weighted bar, and means whereby said weight actuated bar 105 when moving to operate the severing devices resets said impression hammer. 110

14. A coin controlled weight printing machine comprising a printing wheel, a weighing platform, means operated thereby for 115 positioning the printing wheel, an impression hammer, a spring for actuating said impression hammer, a latch for holding said impression hammer from movement under the action of said spring, severing devices, a weight actuated bar for operating said severing devices, a latch for holding said bar in raised position, a coin controlled trip lever, devices controlled thereby for first operating the latch to release the impression hammer and subsequently operating the latch for 120 releasing the weighted bar, and means whereby said weight actuated bar when moving to operate the severing devices resets 125

said impression hammer, said weighted bar operating to reset the coin controlled trip lever on its downward movement.

15. A coin controlled weight printing machine comprising a printing wheel, a weighing platform, means operated thereby for positioning the printing wheel, an impression hammer, a spring for actuating said impression hammer, a latch for holding said hammer from movement, severing devices, a weighted bar for operating the severing devices, a latch for holding said weighted bar in raised position, a coin controlled trip lever, a spring actuated arm controlled by said trip lever, a bar connected to the latch for the impression hammer and disposed in the path of movement of said spring actuated arm, said latch for the weighted bar lying also in the path of movement of said spring actuated arm but positioned relative to said bar so that when said coin controlled trip lever is depressed the hammer will be first moved, after which the latch for the weight actuated bar will be moved, means whereby said bar is moved laterally during the actuation of the latch for the hammer so as to release the spring actuated arm and allow the same to engage the latch for the weight actuated bar, and means whereby said weighted bar returns said hammer to latched position and also returns the spring actuated arm to latched position.

16. A coin controlled weight printing machine comprising a printing wheel, a weighing platform, means operated thereby for positioning the printing wheel, an impression hammer, a spring for actuating said impression hammer, a latch for holding said hammer from movement, severing devices, a weighted bar for operating the severing devices, a latch for holding said weighted bar in raised position, a coin controlled trip lever, a spring actuated arm controlled by said trip lever, a bar connected to the latch for the impression hammer and disposed in the path of movement of said spring actuated arm, said latch for the weighted bar lying also in the path of movement of said spring actuated arm but positioned relative to said bar so that when said coin controlled trip lever is depressed by the coin releasing the spring actuated arm, the latch for the hammer will be first moved, after which the latch for the weight actuated bar will be moved, and means whereby said bar is moved laterally during the actuation of the latch for the hammer so as to release the spring actuated arm and allow the same to engage the latch for the weight actuated bar.

17. A coin controlled weight printing machine comprising a printing wheel, a weighing platform, means operated thereby for positioning the printing wheel, an impression hammer, a spring for actuating said impression hammer, a latch for holding said hammer from movement, severing devices, a weighted bar for operating the severing devices, a latch for holding said weighted bar in raised position, a coin controlled trip lever, a spring actuated arm controlled by said trip lever, a bar connected to the latch

for the impression hammer and disposed in the path of movement of said spring actuated arm, said latch for the weighted bar lying also in the path of movement of said spring actuated arm but positioned relative to said bar so that when said coin controlled trip lever is depressed the hammer will be first moved, after which the latch for the weight actuated bar will be moved, means whereby said bar is moved laterally during the actuation of the latch for the hammer so as to release the spring actuated arm and allow the same to engage the latch for the weight actuated bar, and means whereby said weighted bar returns said hammer to latched position and also returns the spring actuated arm to latched position.

18. A coin controlled weight printing machine comprising a printing wheel, a weighing platform, means operated thereby for positioning the printing wheel, means for projecting a strip ticket into printing position relative to the printing wheel, an impression hammer, means for actuating said hammer, a latch for holding said hammer from movement, severing devices for severing the printed ticket from the strip, a weight actuated bar, a pivoted lever for actuating said severing devices, a dog carried by said weighted bar and adapted to engage said lever so that on the downward movement of said bar said severing devices are actuated by said lever, and means cooperating with said dog for causing the same to release the lever on the downward movement of the bar whereby said severing devices may be separated, and coin controlled means for releasing the impression hammer and subsequently releasing said weighted bar.

19. A coin controlled weight printing machine comprising a printing wheel, a weighing platform, means operated thereby for positioning the printing wheel, means for projecting a strip ticket into printing position relative to the wheel, coin controlled means for printing the ticket and subsequently severing the ticket from the ticket strip including a stationary blade and a movable blade, a spring for moving said movable blade away from the stationary blade, a lever for raising said movable blade into shearing relation with the stationary blade, and means for releasing said lever from the coin controlled actuating means therefor after the strip is severed, whereby said spring may return said movable blade to normal idle position.

20. A coin controlled weight printing machine comprising a printing wheel, a weighing platform, means operated thereby for positioning the printing wheel, means for projecting a strip ticket into printing position relative to the wheel, coin controlled means for printing the ticket and subse-

quently severing the ticket from the ticket strip including a stationary blade and a movable blade, a spring for moving said movable blade away from the stationary blade, a lever for raising said movable blade into shearing relation with the stationary blade, means for releasing said lever from the coin controlled actuating means therefor after the strip is severed, whereby said spring may return said movable blade to normal idle position, said movable blade being pivoted and yieldingly pressed against the stationary blade adjacent its pivot, and a yielding arm adapted to bear against the free end of said movable blade for pressing said movable blade against said stationary blade.

21. A coin controlled weight printing machine comprising a printing wheel, a weighing platform, means operated thereby for positioning the printing wheel, means for projecting a strip ticket into printing position relative to the wheel, severing devices for severing a printed ticket from the strip, a weighted bar, devices actuated thereby for operating said ticket projecting means, devices operated thereby for actuating said severing devices, a latch for holding said weighted bar raised, a coin controlled trip lever and devices operated thereby for releasing said latch, a coin chute for directing a coin against said trip lever, said coin chute having a section thereof adapted to be positioned so as to return the coin, and devices operated by said weighted bar when said bar is raised to latched position for releasing said section of the coin chute so that the coin will be directed against the trip lever.

22. A coin controlled weight printing machine comprising a printing wheel, a vertically movable rack bar operatively connected to said printing wheel for rotating the same, an impression hammer, a spring for operating said impression hammer, a latch for holding said hammer from movement, coin controlled means for releasing said latch, devices connected to the platform of the weighing scales for determining the position of the rack bar for positioning the printing wheel, a coin chute for directing a coin against said coin controlled means for actuating the same, said coin chute being formed so as to provide a circuitous path for the coin so as to permit the printing wheel to come to a standing position before the impression hammer is released.

23. A coin controlled weight printing machine comprising a printing wheel, an impression hammer, severing devices, means for projecting a ticket strip between the severing devices into position to be printed, said means including a weight operated bar, a latch for holding said weight operated bar in raised position, a coin controlled trip lever for releasing said latch, a rod connected to said weighted bar for raising the same,

means for pivotally supporting the platform of the weighing scales on the weighing frame, means operated by the swinging movement of the platform on its pivot for raising the rod to set the weighted bar, said means operated by the platform being constructed so as to be released from the rod after the weighted bar is set whereby the platform of the scales can be properly positioned for weighing an individual, and means whereby the weight of the individual on the platform positions the printing wheel for printing the weight of the individual.

24. A coin controlled weight printing machine comprising a printing wheel, a platform on which the individual stands, a weighing frame on which said platform is mounted, means for connecting said weighing frame to said printing wheel whereby the printing wheel is positioned by the weight of the individual, means for projecting a ticket strip into printing position relative to the printing wheel, coin controlled means for printing said ticket and for subsequently severing the ticket from the strip, said means including a weighted bar, a latch for holding said weighted bar in raised position, a rod connected to said weighted bar for raising the same, said platform being pivotally mounted on said weighing frame, a weighted arm for normally holding the platform elevated relative to the weighing frame, a stop for limiting the upward movement of the platform, a lever pivoted on the weighing frame and extending to a point beneath the rod for lifting the weighted bar, a latch pivotally mounted on the platform and adapted to engage the end of the lever whereby swinging movements of the platform impart the swinging movements to the lever for raising the rod, and means for releasing the latch on the downward movement of the platform after the weighted bar has been raised to set position.

25. A coin-controlled weight printing machine comprising a printing wheel, means for feeding an accordion folded ticket strip and projecting the ticket at the end of the strip into printing position, and coin-controlled actuating means for impressing the ticket against the printing wheel and for subsequently severing said ticket from the strip, said ticket strip being folded so that each folded section of the strip includes a series of complete tickets whereby the tickets fed to the printing wheel while held in storage are neither folded or curved.

26. A coin-controlled weight printing machine comprising a printing wheel, a weighing platform, means operated thereby for positioning the printing wheel, means for feeding an accordion folded ticket strip and projecting the ticket at the end of the strip into printing position, coin-controlled actuating means for pressing the ticket against

the printing wheel and for severing said ticket from the strip after it is printed, and a storage receptacle for said accordion folded strip, said receptacle being constructed so 5 that the stored portion of the strip may be lifted from the receptacle and a new supply of accordion folded ticket strip attached to the end of the strip which is being fed to the printing mechanism before said strip on 10 which the printing mechanism is operating is exhausted.

27. A combined weight printing and height measuring mechanism including in combination, a platform weighing mechanism including a printing wheel connected to said platform, coin-controlled means for presenting a ticket to the printing wheel, for printing the ticket and discharging the printed ticket, means in which power may 15 be stored by the movement of the platform for actuating said coin-controlled means when released, a casing in which the printing 20

wheel and coin-controlled mechanism is located, a mirror in the front face of the casing provided with a vision slot, a member 25 located in rear of the slot and bearing a scale for indicating the height of the individual standing on the platform by the image reflected in the mirror, means for supporting said scale whereby the same may be concealed from view or moved so as to be viewed through said slot, a spring for turning said scale bearing member so as to expose the scale to view through the slot, a 30 latch for holding said scale bearing member so as to conceal the scale, means controlled by the movement of the platform for turning said scale bearing member to conceal the scale, and an independent coin-controlled mechanism for releasing the latch for said 35 scale bearing member.

In testimony whereof, I affix my signature.

VINCENT F. SLEZAK.
